TO FRANK F. COGGIN, OF MALDEN, MASSACHUSETTS.

FLEXIBLE CONDUIT.

1,285,291.

Specification of Letters Patent. Patented Nov. 19, 1918.

Application filed June 3, 1918. Serial No. 238,039.

To all whom it may concern:

Be it known that I, MILTON P. McLAUGHLIN, a citizen of the United States, residing at Wakefield, in the county of Middlesex and State of Massachusetts, have invented new and useful Improvements in Flexible Conduits, of which the following is a specification.

This invention relates to the flexible portions of conduits employed on railway trains for conducting fluids such as steam or air, said flexible portions being located between train units and conforming to independent movements of said units.

The object of the invention is to provide a simple and durable flexible conduit adapted to permit the passage of fluids with less frictional resistance than heretofore, so that a fluid may pass without serious frictional resistance from end to end of a train.

The invention is embodied in the improvements which I will now proceed to describe and claim.

Of the accompanying drawings forming a part of this specification,—

Figure 1 is a side elevation of a flexible conduit embodying the invention.

Fig. 2 is a section on line 2—2 of Fig. 1, and a plan view of the conduit below said line.

Fig. 3 is a section on line 3—3 of Fig. 2.

Fig. 4 is a section on line 4—4 of Fig. 2.

Fig. 5 is a section on line 5—5 of Fig. 2.

Fig. 6 is a side view of the recessed annular gasket hereinafter described.

Fig. 7 is a section on line 7—7 of Fig. 6.

Fig. 8 is a view similar to Fig. 1, showing a different embodiment of the invention.

Fig. 9 shows in perspective the members of one of the two elbow-shaped conduit elements shown by Fig. 1, said members being separated.

The same reference characters indicate the same or similar parts in all of the figures.

My improved conduit is substantially U-shaped and includes two terminal conduit parts 12, each having an external screw-thread 13 at its outer end whereby it is adapted to be coupled to a fixed conduit part, not shown, on a train unit. The inner end portion 12^a of each terminal conduit part 12 constitutes a male swivel joint member which is preferably enlarged and provided with an annular shoulder 14. To the inner end portions of the terminal parts 12

are secured internally cylindrical hinge socket members 15, the axes of which are at right angles with the axes of the terminal members, each member 15 being provided with a lateral sleeve or nipple 16, forming 60 a female swivel joint member internally formed to fit the male joint member 12^a of a terminal coupling part 12, and threaded to engage a gland 17 between which and the shoulder 14 is interposed a compressible 65 gasket 18. Each socket member 15 and nipple 16 constitutes a T head forming a part of a swivel joint and hinge connection.

The nipple 16 constitutes a part of the fluid passage through the conduit, as shown 70 by Figs. 3 and 4.

Fitted to turn or rock in the socket member 15 is an externally cylindrical fluid-conducting hinge pintle member 19, closed at its ends and having a transverse fluid-conducting passage formed as here shown by diametrically opposite openings 20 and 21, and the chambered interior of the pintle member, said openings and chambered interior forming portions of the conduit, the 80 opening 21 being tapped to engage the threaded outer end of an elbow-shaped conduit part 22 which extends through a segmental slot 23 formed in the side of the socket member 15 opposite the nipple 16. 85 The length of said slot is such that the conduit part 22 is adapted to oscillate as indicated by full and dotted lines in Fig. 1, the pintle member 19 being therefore adapted to turn or rock in the socket member. 90

The elbow-shaped member 22 includes a relatively vertical portion, a relatively horizontal portion, and an arcuate bend connecting said portions and having a radius of considerable length, so that the bend is 95 adapted to change the direction of fluid passing through the conduit, without objectionable frictional resistance.

To form a fluid-tight joint around the opening 20 of the pintle member, I provide a compressible annular or tubular fluid conducting gasket 25, preferably of soft rubber formed externally to fit the interior of the nipple 16 and having recesses 26 in its inner end, conforming to a portion of the periphery of the pintle member 19, said recesses collectively forming a face entirely surrounding the opening 20.

The gasket 25 is yieldingly pressed against the pintle member 19 by the spring 27 seat- 110

ed at one end on an internal shoulder 28 in the terminal member 12, and at its opposite end on a metal ring 29, which in turn is seated on the outer end of the gasket 25, and has a beveled face exerting outward pressure on the gasket.

One end of the socket member 15 is left open and is tapped to engage a screw-threaded cap or closure 30 (Fig. 3). When the 10 conduit part 22 is disconnected from the pintle member 19, and the cap 30 is removed, the pintle member may be inserted in the socket member in position to be engaged with the conduit part 22.

15 The inner end of the horizontal portion of each elbow-shaped conduit part 22 constitutes a male swivel joint member 22^a which has a relatively horizontal axis and is preferably enlarged and provided with an annular shoulder 14^a. 31 represents an internally cylindrical hinge socket member, the axis of which is parallel with the axis of the socket member 15. The socket member 31 is provided with a laterally extending sleeve 25 or nipple 32 constituting the female member of a swivel joint and a portion of the conduit, the axis of said female members being coaxial with the axis of the horizontal portion of the member 22. Said nipple has at its 30 outer end a gland 33, a compressible gasket 18^a being interposed between the gland and the shoulder 14^a.

34 represents an externally cylindrical hinge pintle member fitted to turn in the 35 socket member 31, and having diametrically opposite openings 35 and 36 constituting portions of the conduit, the opening 36 being adapted to engage the externally threaded outer end of a conduit part 37 projecting 40 through a segmental slot 38 in the socket member 31, said slot permitting the pintle 34 to turn in the socket member, and the conduit part 37 to oscillate in the slot. A tubular gasket 25^a, similar to the gasket 25, is employed to form a fluid-tight joint surrounding the opening 35, said gasket being pressed by a spring 27^a and a ring 29^a against the pintle member 34.

There are two meeting conduit parts 37 50 arranged end to end, and their meeting ends are separately connected by suitable coupler heads conventionally shown at 40. Said heads may be similar to those in common use in flexible conduits, and permit the meeting 55 conduit parts to be disconnected by hand and by abnormal strain such as is exerted when two train units are pulled apart. When the meeting conduit parts 37 are connected, they form a rigid conduit portion 60 connecting the two hinge pintle members 34.

When the conduit as a whole is in normal working condition, the terminal parts 12 being normally spaced apart, the position of the elbow-shaped parts 22 and meeting parts 37 is 65 as indicated by full lines in Fig. 1. When the

terminal parts 12 are more widely separated, the parts 22 swing to or toward the positions shown by dotted lines, the meeting parts 37 moving vertically sidewise to or toward the dotted line position shown by said figure. 70

It will be seen by reference to the drawings that the longitudinal axes of the conduit parts 12, 22, and 37 are in the same plane, and that the axes of the passages of the swivel joint and hinge connections are 75 in the same plane with the axes of said conduit parts, so that the only bends in the conduit are those due to the U-shape thereof. The longitudinal axes of the gaskets 25 and 25^a are in the same plane with the axes of 80 said conduit parts and passages. The conduit is therefore free from lateral bends, so that the frictional resistance to the passage of fluid through the conduit is materially less than would be the case if the conduit 85 presented lateral bends in addition to the general bend due to its U-shape.

The construction shown by Figs. 1 and 2 is adapted for use between cars, two meeting 90 conduit parts 37 being employed, these being detachably connected or coupled together end to end.

That portion of the described coupling which includes a fixed terminal conduit part such as 12 at one end attachable to a car, 95 and a movable part such as 37 at the opposite end, provided with a coupler head, constitutes a coupling element, which, when attached to one car, may be coupled up with a coupling element of a different type on 100 another car, the part 12 constituting the fixed terminal, and the part 37 the movable terminal of said element. I therefore do not limit myself to a coupling which includes two duplicate coupling elements. 105

It will be seen that the fixed terminal conduit part 12 is connected with the elbow-shaped conduit part 22, by an outer swivel-joint-and-hinge connection which includes the members 12^a, 16, 15 and 19, and that each 110 movable terminal or meeting conduit part 37 is connected with the elbow-shaped conduit part by an inner swivel-joint-and-hinge connection which includes the members 22^a, 32, 31 and 34. 115

The members 22^a and 32 permit the terminal part 37 to turn on a horizontal axis which is coaxial with the axis of the horizontal portion of the elbow-shaped coupling part. This provision is important, because 120 it prevents liability of injury to the conduit by a crosswise inclination of train units due to imperfections in the track, or to the fact that a portion of one rail is higher than the other. This provision, and the provision for 125 the swinging of the part 37 on a horizontal axis at right angles with the axis of its turning movement, enable the part 37 to conform to various movements of one train unit relatively to the other. 130

When the invention is embodied in a conduit for use between a locomotive engine and its tender, or for any purpose not requiring a separable connection between the elbow-shaped conduit parts 22, the construction may be as indicated by Fig. 8, in which the elbow-shaped parts 22^a, 22^b are connected by a single swivel joint and hinge connection. Said connection includes a hinge socket member 31^a similar to the socket member 31 and having a sleeve or nipple 31^b constituting a female swivel joint member adapted to turn on a male swivel joint member on the part 22^b. The socket member 31^a is adapted to 10 turn on a pintle member not shown, similar to the pintle member 34 and tapped to engage the conduit member 22^c. This form of flexible conduit is adapted to conduct oil from the tender to the fire-box of an oil-burning locomotive. It may also conduct 20 any other fluid.

Each embodiment of the invention comprises a central flexible fluid-conducting means between the horizontal portions of 25 the elbow-shaped conduit parts, including coacting swivel joint members substantially coaxial with said horizontal portions, and coacting hinge members permitting upward and downward movements of said horizontal portions and of the central conducting means. Said swivel joint members are 30 essential to the durability of the conduit and prevent liability of breakage of the same at the central portion by a transverse inclination of one train unit relatively to the other due to track imperfections and other causes.

I claim:

1. A flexible conduit element comprising 40 a terminal conduit part adapted to be fixedly secured, a movable terminal conduit part provided with a coupling member, an intermediate elbow-shaped conduit part, and flexible fluid-conducting connections between said parts, including hinge pintle members having closed ends and transverse fluid-conducting passages, the longitudinal axes of said conduit parts and passages being in substantially the same plane, so that 45 the conduit is free from lateral bends, said elbow-shaped part including a relatively vertical portion, a relatively horizontal portion, and an arcuate bend connecting said portions and in the same plane therewith.
- 50 55 2. A flexible conduit element comprising a terminal conduit part adapted to be fixedly secured, a movable terminal conduit part provided with a coupling member, an intermediate elbow-shaped conduit part, flexible fluid-conducting connections between said parts, including externally cylindrical hinge pintle members having closed ends and transverse fluid-conducting passages, the longitudinal axes of said conduit parts and 60 65 passages being in substantially the same

plane, so that the conduit is free from lateral bends, compressible fluid-conducting annular gaskets having recessed inner ends conforming to portions of the peripheries of said pintle members, and means for yieldingly pressing said gaskets against the pintle members, the longitudinal axes of said gaskets being in substantially the same plane with the axes of said conduit parts and passages. 70

3. A flexible conduit element comprising a terminal conduit part adapted to be fixedly secured, a movable terminal conduit part provided with a coupling member, an intermediate elbow-shaped conduit part including a relatively vertical portion, a relatively horizontal portion and an arcuate bend connecting said portions and in substantially the same plane therewith, flexible fluid-conducting connections between the fixed terminal part and the vertical portion of the elbow-shaped part having means permitting said vertical portion to turn on a relatively vertical axis and to swing on a relatively horizontal axis, and flexible fluid-conducting connections between the horizontal portion of the elbow-shaped conduit part and the movable terminal part including male and female swivel joint members permitting the movable terminal part and its coupling member to turn on an axis substantially coaxial with said horizontal portion, and coacting hinge members permitting upward and downward movement of said movable terminal part and its coupling member. 90

4. A flexible conduit element comprising a terminal conduit part adapted to be fixedly secured, and provided with a male swivel joint member having a relatively vertical axis, a movable terminal conduit part provided at one end with a hinge pintle member whose axis is relatively horizontal and is at right angles with the axis of the movable conduit part, an intermediate elbow-shaped conduit part including first, a relatively vertical portion provided with a hinge pintle member whose axis is relatively horizontal and is at right angles with the axis of the vertical portion, and secondly, a relatively horizontal portion provided 105 with a male swivel joint member coaxial with the horizontal portion, and two fluid-conducting T heads, each including a female swivel joint member and a hinge socket member, said heads connecting the said conduit parts, and permitting the vertical portion of the elbow-shaped conduit part to turn on a relatively vertical axis and to swing on a relatively horizontal axis, and the movable terminal conduit part to swing 110 on a relatively horizontal axis at right angles with said horizontal portion and to turn on an axis coaxial with the latter. 120

5. A flexible U-shaped conduit, comprising terminal conduit parts adapted to be 130

fixedly secured, and each provided with a male swivel joint member having a relatively vertical axis, elbow-shaped conduit parts each including first a relatively vertical portion provided with a hinge pintle member whose axis is relatively horizontal and is at right angles with the axis of the said vertical portion, and secondly a relatively horizontal portion provided with a 10 male swivel joint member coaxial with said horizontal portion, fluid-conducting T heads connecting said fixed and elbow-shaped parts, each head including a female swivel joint member and hinge socket member, said 15 heads permitting the vertical portions of the elbow-shaped parts to turn on relatively vertical axes and to swing on relatively horizontal axes, and central flexible fluid-conducting means between the horizontal portions of the elbow-shaped conduit parts, including coacting swivel joint members substantially coaxial with said horizontal portions and coacting hinge members permitting upward and downward movements of 20 said horizontal portions and of the central conducting means.

6. A flexible conduit element comprising two spaced apart conduit parts, the longitudinal axes of which are in substantially 25 the same plane, one of said parts having a male swivel joint member coaxial therewith, and the other part having a hinge pintle member whose axis is at right angles with the axis of the swivel joint member, a T 30 head interposed between and connecting said conduit parts with their longitudinal axes in substantially the same plane, said head including a female swivel joint member and a hinge socket member, comple-

mental respectively to the male swivel joint member and the pintle member, said pintle member being closed at its ends and having a transverse fluid-conducting passage in the same plane with the said conduit parts, a compressible fluid-conducting annular gasket 40 having a recessed inner end conforming to a portion of the periphery of said pintle member, and means for yieldingly pressing said gasket against the pintle member, the longitudinal axis of said gasket being in 45 substantially the same plane with the axes of said conduit parts and passage.

7. A flexible conduit including an internally cylindrical hinge socket member having a tubular nipple at one side and a segmental slot in the opposite side, a fluid-conducting externally cylindrical hinge pintle member formed to turn in said socket member, a compressible annular gasket in said nipple having a recessed inner end conforming to a portion of the periphery of the pintle member, means for yieldingly pressing said gasket against the pintle member, said means including a spring-pressed ring having a beveled face adapted to press one end 65 of said gasket radially outward, a conduit part attached to and communicating with the interior of the socket member, a conduit part attached to and communicating with the pintle member and extending through 70 the slot in the socket member, and a gland having a screw-thread engagement with the outer end of the nipple and adapted to confine said spring in its operative position.

In testimony whereof I have affixed my 75 signature.

MILTON P. McLAUGHLIN.
